UNITED STATES PATENT OFFICE.

CLYDE H. BLISS, OF PORTLAND, OREGON.

TAMPER.

Application filed April 9, 1927. Serial No. 182,430.

The invention relates to tampers and has as an object the provision of a mechanical tamper adapted for use with sand-lime, or concrete brick machines.

5 It is a further object of the invention to provide a tamper acting by its own weight and assisted by revolution of a non-cylindrical portion producing a jarring action by virtue of the revolution thereof.

10 It is a further object of the invention to provide a tamper having a parallel motion attachment to bring the tamping elements into the desired position for action.

15 It is a further object of the invention to provide a tamper having a continuous rotating part normally held out of tamping position and automatically brought to such position by gravity when the tamper is brought to position of use.

20 It is a still further object of the invention to provide a tamper adapted for use with a brick machine such as shown in prior patent to applicant No. 1,508,212, granted September 9, 1924.

25 Further objects of the invention will appear from the following description when read in connection with the accompanying drawings showing an illustrative embodiment of the invention and wherein:

30 Figure 1 is a detail side elevation of a portion of a brick machine having the tamper of the present invention applied thereto; Fig. 2 is a detail central vertical section

on line 2—2 of Fig. 1; and

35 Fig. 3 is a detail vertical section on line 3—3 of Fig. 2.

The brick machine of the former patent comprises a series of mold spaces 10 in which material for formation of bricks is automatically deposited by the machine and in which it is desired to tamp the material.

40 The tamper of the present invention comprises a series of bearing portions or feet 11 carried by a bar 12, the feet 11 being spaced apart a correct distance to enter the spaces 10, the superficial area of the feet being substantially equal to the interior dimension of the spaces 10.

45 The bar 12 is shown as having upwardly projecting arms 13, 14, the two ends of said arms being provided with slots 15, 16 for reception of the revoluble member to produce the jarring action.

50 The jarring member in the illustrated embodiment comprises a rectangular bar 17 preferably square in cross section provided

with cylindrical members 18, 19 desirably formed integrally therewith and projecting through the slots 15, 16.

To cause revolution of the member 17, belt pulley 20, 21 is rigidly secured to each of the members 18, 19. The members 18, 19 are desirably journaled in blocks 22, 23 which have cylindrical journal bearings and an outer formation fitting the slots 15, 16 and 65 vertically slidable therein.

The tamper is shown as mounted upon arms 24, 25 journaled upon the members 18, 19 and pivoted upon the uprights 26 of the machine.

70 To provide parallel motion of the tamper when raised from and lowered to position for actuation, the upper ends of projections 13, 14 are shown as connected by means of links 27, 28, the opposite ends of the links being 75 pivoted as at 29 to the uprights 26.

To drive the rotating member 17, belts, one of which is shown at 30, are passed about pulleys 20, 21 and about pulleys, one of which is shown at 31, rigidly mounted on the shaft 80 32 upon which the arms 24, 25 are mounted for their pivotal action. A driving pulley not shown is provided upon the shaft 32 for driving the belts and by virtue of the center of the belt pulleys being located upon the center of movement of the arms 24, 25, the belts 30 will at all times have the same tension whether the tamper is in or out of position for action.

85 The arms 24, 25 are desirably extended beyond the shaft 32 and provided with counterweights, one of which is shown at 33, to balance the weight of the tamper.

90 The tamper may be automatically brought to operative position by means of a link 34 connected to mechanism of the nature shown in the former patent No. 1,508,212 above referred to.

95 To take the wear of the rotating member 17 during its jarring action, the bar 12 is shown as shod with a wear plate 35 desirably formed of hardened steel and shown as secured to bar 12 by means of bolts 36, by removal of which bolts the wear plate may be 100 readily renewed when worn.

105 When the tamper is lifted out of operative position by the links 34, the weight of the tamper will cause the blocks 22, 23 to rise in the slots 15, 16, thus lifting the bar 17 from contact with the wear plate 35 and the bar 17 may therefore be continuously rotated during the operation of the machine.

2 without causing a jarring action upon the tamper except while it is lowered for use.

When the tamper is lowered to the position shown in Fig. 1, the weight of bar 5 17 will cause the blocks 22, 23 to ride to the bottom of the slots by action of gravity upon the bar 17, when the bar 17 will be caused to rise by contact at its corners with the wear plate 35 and to fall thereon to provide 10 a series of momentum impacts which in combination with the weight of the entire tamper provides a rapid tamping action upon the material in the spaces 10.

Minor changes may be made in the physical embodiment of the invention within the scope of the appended claims without departing from the spirit thereof.

I claim:

1. A tamper comprising in combination, 20 an impact shoe, a non-cylindrical member resting upon said shoe by gravity while the tamper is in action, means to revolve said member and means to simultaneously lift said member from jarring position and to 25 lift said shoe.

2. A tamper comprising in combination, an impact shoe, a non-cylindrical member adapted to rest upon said shoe, means for causing revolution of said member, means 30 for simultaneously lifting said member from impacting position and for lifting said shoe, and means to provide a parallel motion of the shoe when moved from and to operative position.

3. A tamper comprising in combination, a bar, a plurality of impacting shoes mounted upon said bar in spaced position, a member projecting from said bar having ways, a non-cylindrical member slidably 40 mounted in said ways and adapted to rest by gravity upon said bar when the shoes are in operative position, and means acting through said member to raise the member in the ways and to raise said bar from operative position.

4. A tamper comprising in combination,

a bar, an impact shoe projecting from one side of said bar, arms projecting from the opposite side of said bar and having slots, a polygonal bar having cylindrical portions 50 rotatable and slidable in said slots, means for rotating said last named bar and means for lifting the tamper from operative position acting upon said portions whereby to also lift said portions in said slots, contact 55 between said bars preserved by gravitation when the impact shoe rests upon material to be tamped.

5. A tamper comprising in combination, a frame comprising a body and spaced slotted arms projecting from one side thereof, an impact shoe projecting from the opposite side of said frame, a wear plate mounted on said body, a polygonal bar bearing on said plate during operation of the tamper 60 and having cylindrical portions journaled in the slots of said arms, means to revolve said bar to cause jarring action of said frame, means acting on said bar to lift the portions in the slots and by engagement 70 with the upper ends of said slots to lift the frame out of operative position whereby the bar may be continuously rotated without jarring action when the tamper is lifted to 75 inoperative position.

6. A tamper comprising in combination, a frame comprising a body and spaced slotted arms projecting from one side thereof, a tamping shoe projecting from the opposite side of the frame, journal blocks slid- 80 able in the slots of said arms, a wear plate carried by said body, a polygonal bar having cylindrical portions journaled in said blocks, said bar resting by gravity on said plate during tamping action, means to re- 85 solve said bar, means acting through said bar cylindrical portions to first lift the bar from contact with said plate and by continued movement to lift the frame from tamping position during continued revolution of the bar.
